W. W. KEENE

PORTABLE SPRAYER

Filed Jan. 16, 1922

Inventor
Waite W. Keene
By Geo B Rawlings,
Attorney

UNITED STATES PATENT OFFICE.

WAITE W. KEENE, OF QUINCY, MASSACHUSETTS, ASSIGNOR TO MASURY-YOUNG COMPANY, OF CHARLESTOWN, MASSACHUSETTS, A CORPORATION OF MASSACHUSETTS.

PORTABLE SPRAYER.

Application filed January 16, 1922. Serial No. 529,470.

To all whom it may concern:

Be it known that I, WAITE W. KEENE, a citizen of the United States, and a resident of Quincy, in the county of Norfolk and 5 Commonwealth of Massachusetts, have invented certain new and useful Improvements in Portable Sprayers, of which the following is a specification.

This invention relates to portable sprayers, and particularly to a sprayer for spraying floors with oil.

In such sprayers, it is desirable that the mechanism for operating the discharge valve be disposed for convenient manipulation by 15 the same hand with which the user carries the supply tank, leaving the other hand of the user free to operate the pump from time to time to maintain a pressure of air upon the oil or other liquid within the tank.

According to my invention, the tank is 20 provided with a vertically slotted carrying handle and the discharge valve is opened by direct upward lift upon a spring-tensioned pull stem which is operatively connected at 25 one end with said valve and at its other end is bent to provide a finger hook disposed through the slot of the carrying handle so as to lie under the cross bar of said handle conveniently within reach of the forefinger 30 of the same hand with which the user grasps said handle. This arrangement not only provides a simple, positive and conveniently operable actuating mechanism by which the valve may be opened and held open with 35 the minimum of effort as the user carries the tank over the floor, but permits the valve and spraying nozzle to be located beneath the tank bottom at substantially the edge thereof.

Another feature of my invention consists 40 in the combination with a spraying nozzle so located, of a supporting base depending from the tank bottom as an annular enclosing skirt or shell and provided opposite the discharge nozzle with an outlet opening through which the oil may be discharged from said nozzle outwardly over the floor.

These and various other features of advantages which will appear more fully hereinafter are secured in the device of the pres-

ent invention, the construction and operation of which, together with a selected embodiment which well illustrates the principles involved, is described and shown in the accompanying specification and drawings, 55 and the characteristic features of novelty particularly pointed out in the appended claims. Throughout the specification and drawings like reference characters are correspondingly applied, and in the drawings; 60

Figs. 1 and 2 are elevations at right angles to each other of a portable sprayer in accordance with my invention.

Figs. 3 and 4 are plan and side views respectively of the spraying nozzle and particularly showing the rocker arm for the discharge valve.

Fig. 4^a is a section on the line 4—4 of Fig. 4.

Figs. 5 and 5^a are detail views showing a 70 modified form of connection between the finger-operated pull stem and the rocker arm for the discharge valve.

Figs. 6, 7 and 8 are detail views showing a modification of the guide for the pull-stem, 75 Fig. 7 being a section on the line 7—7 of Fig. 6, and

Fig. 9 shows a further modification of the connection detailed in Figs. 5 and 5^a.

I have indicated at 1 a portable tank of 80 suitable capacity and preferably of cylindrical form, and at 2 a supporting base depending from the tank bottom as an annular enclosing skirt or shell which is preferably cut out between its ends, as indicated 85 at 3, to provide an outlet opening at the front of the tank through which the spraying nozzle 4 of the tank is exposed whereby the liquid expelled through the elongated discharge port 5 of said nozzle may be distributed 90 outwardly through said opening onto the floor.

As appears in Figs. 1 and 2, the nozzle 4 is disposed beneath the tank bottom at substantially the center thereof, and is connected with the interior of the tank by a supply pipe 6.

Rotatable within the nozzle upon journals 7 Figs. 3 and 4, is a valve plug 7' having a recess 7² communicating with the pipe 6 and 100

a discharge passage 7^a leading from said recess and adapted to connect with the discharge port 5 of the nozzle to establish and destroy the communication between the 5 pipe 6 and the port 5, according to the position of the valve.

Fast to the valve at one end thereof is a rocker arm 8 which is bent upon itself to extend along the nozzle to substantially a 10 point opposite the pipe 6, Fig. 3, and thence outwardly at right angles. In Figs. 1 and 2, the outer end of the arm 8 is shown as perforated to receive the lower end of a pull stem 10 by means of which the valve is 15 opened and closed.

In the modification shown in Fig. 3, the outer end of said arm is bifurcated to provide a slot 9 within which the lower end of the stem 10 is slidably engaged.

20 In the modification shown in Figs. 5 and 5^a, the sides of the stem 10 are reduced for a portion of their length to leave an intermediate web 11 which is disposed in the open-ended slot 9 of the arm.

25 In the modification shown in Fig. 9, the arm and stem are connected by a pin and slot 12.

The pull stem 10 extends vertically along the side of the tank and terminates at its 30 upper end in an inturned finger hook 10' by means of which the stem may be raised to open the valve against the action of spring 13 coiled about said stem. At its lower end, the spring abuts a collar 14 pinned to the 35 stem and at its upper end bears against a guide which in the form shown in Figs. 1 and 2 is a simple angle iron comprising a horizontal basal portion 15 through which the stem is passed and a vertical side portion 15^a extending from the outer edge of 40 said horizontal portion and terminating in an inturned horizontal flange 15^b.

Fast to the top of the tank is a carrying handle 18 comprising spaced attaching portions 45 and a horizontal cross-piece connecting said portions. The outer attaching portion of the handle is slotted longitudinally, as indicated at 19, and the inturned hook end 10' of the pull stem is entered through said slot 50 and lies under the cross-piece of the handle so that the forefinger of the hand which grasps the carrying handle may be laid under said hook end and the pull stem raised to open the valve by simply crooking the 55 finger.

When the pull stem is raised to open the valve, the spring 13 is compressed. When said stem is released, said spring expands to return the stem and rocker arm to normal 60 position, thereby positively closing the valve. The upward movement of the stem is limited by the abutment of a stop 29 thereon with a set screw 30 which is mounted for vertical adjustment upon the flange 15^b of 65 the guide 15, and the downward travel of

said stem is limited by the abutment of said stop with the basal portion of the guide.

As an alternative construction, the guide 15 may be formed as detailed in Figs. 6, 7 and 8 wherein said guide is shown as forked 70 to straddle the web of an attaching lug 16' which is soldered to the tank wall, the guide being fastened to the web by rivets 17. With this construction, the finger pull may be entered laterally through the slot 19 of 75 the carrying handle, as indicated by the arrow in Fig. 8, in assembling the device, and moreover, the upper end of the slot itself serves as a stop to limit the opening of the valve.

80 The hand pump of the tank is indicated at 34 and the funnel for the filling opening at 35.

Various other modifications may obviously be resorted to within the limits of the appended claims.

I claim:

1. A sprayer comprising a portable tank having a discharge port through its bottom wall, a rotatable valve disposed below said wall and controlling said port, a carrying handle mounted at the top of said tank and comprising spaced attaching portions and a cross-piece connecting said portions, a pull member operatively connected to said valve 90 and having at its upper end an inwardly extending finger hook disposed across the tank top to lie beneath the cross-piece of the carrying handle whereby said pull member may be raised to open the valve by the forefinger 95 of the same hand with which the user grasps the carrying handle, and a spring opposing the raising movement of said pull member.

2. A sprayer comprising a portable tank having a discharge port through its bottom wall, a rotatable valve disposed below said wall and controlling said port, a carrying handle mounted at the top of said tank and comprising spaced attaching portions and a cross-piece connecting said portions, one of 100 said attaching portions having a longitudinally extending slot, a pull stem operatively connected to said valve and having at its upper end an inwardly extending finger hook disposed through said slot of the carrying handle to lie beneath the cross-piece thereof whereby the stem may be raised to open the valve by the forefinger of the same hand with which the user grasps the cross-piece 105 of the carrying handle, and a spring opposing the raising movement of said stem.

3. A sprayer comprising a portable tank having a discharge port, a rotatable valve controlling said port, a pull stem operatively connected to said valve, a guide for said stem having spaced stop portions one of 125 said stop portions adjustable relative to the other, a stop on said stem between said stop portions and adapted to contact said stop portions to limit the movement of said stem 130

in either direction, and a spring opposing the raising movement of said stem.

4. A sprayer comprising a portable tank, an annular skirt depending from the tank bottom and constituting a supporting base for said tank, said skirt having an outlet opening through its side wall, a spraying

nozzle within the skirt and connecting with the interior of the tank and having a discharge port opposite said outlet opening, ¹⁰ and a rotatable valve controlling said port.

In testimony whereof I affix my signature.

WAITE W. KEENE.
